SAND SCREEN

Filed Oct. 15, 1928

FIG. 1

UNITED STATES PATENT OFFICE

WALTER H. WANGELIN, OF ST. LOUIS, MISSOURI

SAND SCREEN

Application filed October 15, 1928. Serial No. 312,449.

This invention relates generally to foundry apparatus and particularly to an improved sand screen adapted for use in blending, mixing, aerating, and generally preparing foundry sand for use in molds, the predominant object of the invention being to produce an apparatus of this type which includes as an integral, internal part thereof a sieve through which the sand acted on by the apparatus passes during its passage through the apparatus, whereby the hard particles or foreign elements in the sand are separated therefrom so that only properly prepared, usable sand is discharged from the apparatus.

Prior to this invention sand screens of the type to which my invention belongs have been produced and have been used in foundries, but these apparatus included rotatable elements which rotated very slowly and the sand being acted on by the apparatus passed through the sieves thereof only by gravity. Also the nature of the sand screens formerly used necessitated that they be quite large and therefore they were ordinarily not portable. The sand screens of the type referred to, due to the above and other well known deficiencies in connection therewith did not operate with the desired efficiency and this prevented such apparatus from being universally used.

Recognizing the disadvantages in connection with the use of the sand screens formerly employed I have devised the sand screen disclosed herein which briefly stated includes a rotary sieve which moves at a very high rate of speed with the impellers by which the sand is discharged from the apparatus, whereby the sand being acted on is forced through the rotary sieve by centrifugal force and suction of air. The rotary sieve referred to is enclosed within the apparatus and when sand is introduced into the apparatus it passes through said sieve before said sand is acted on by the impellers, hence the sand that is discharged from the apparatus by contact therewith of the impellers is usable sand from which hard particles and foreign elements have been removed. In addition to separating undesir-

able matter from the sand passing through the apparatus the rotary sieve serves to aid the impellers in thoroughly blending and mixing the sand so that said sand, after being aerated when projected through the air from the outlet of the apparatus, is properly prepared for use in molds.

Fig. 1 is a front elevation of my improved sand screen.

Fig. 2 is a vertical section of the sand screen illustrated in Fig. 1.

Fig. 3 is a fragmentary vertical section showing the discharge outlet of the apparatus.

In the drawing, which illustrates one embodiment merely of the invention, A designates my improved sand screen generally, said sand screen including a housing B having an inlet C and an outlet or discharge D. The housing B is comprised of a front wall 1 and a rear wall 2 (Fig. 2) which are spaced apart from each other, said walls 1 and 2 being provided with flanges 3 and 4 respectively through which suitable fastening devices 5 pass to secure said walls to a suitable support 6, which support, if desired, may be a portion of a truck or other portable device. The walls 1 and 2 are provided with annular grooves 7 which are alined with each other in the direction of the depth of the apparatus as shown in Fig. 2, and 8 designates an annular or cylindrical wall the opposite edge portions of which are seated in the oppositely disposed grooves 7. Formed integral with or secured to the cylindrical wall 8 is a spout 9, said spout being extended outwardly from the cylindrical wall and constitutes the outlet or discharge passageway of the apparatus.

At the extreme upper portion of the apparatus I provide the front and rear walls 1 and 2 with ears 10, and 11 designates a tie bolt which is extended through apertures formed in said ears, said tie bolt having a head portion at one end thereof and a screw-threaded portion at its opposite end which is adapted to receive a nut, which head portion and nut contact with the ears 10 on the walls 1 and 2 in a manner to cause the upper portions of said walls to be drawn

toward each other when the nut is screwed inwardly on the tie bolt. The spacing of the walls 1 and 2 at the lower portions thereof is such that in the absence of something preventing it, the cylindrical wall may be rotated, the opposite edge portions of said cylindrical wall moving relatively to the walls of the grooves 7.

It is obvious in view of the arrangement just described that if it be desired to elevate or depress the outlet spout 9 to vary the angle of the stream of sand being discharged from the apparatus, this may be done by merely unscrewing the nut on the tie bolt 11. This will permit the upper portions of the walls 1 and 2 to move away from each other slightly thus relieving the frictional grip between the edge portions of the cylindrical wall 8 and the walls of the grooves 7 and permitting said cylindrical wall to be rotated to bring the spout 9 to the desired position. When the spout 9 has been properly positioned the nut on the tie bolt 11 will again be screwed inwardly on said tie bolt 25 to cause the walls 1 and 2 to again frictionally grip the edge portions of the cylindrical wall 8 whereby accidental rotary movement of said wall will be prevented.

The front wall 1 of the apparatus is provided with a large central opening 12 as shown clearly in Fig. 2, and 13 designates a plate which covers said opening. The plate 13 is secured to the front wall 1 by suitable fastening devices and said plate is provided with an opening 14 which serves as the inlet opening of the apparatus. Formed integral with the plate 13 or secured thereto is a chute or inclined trough 15 which leads to the opening 14 so that any material introduced into said chute will pass through said opening. At the lower portion of the plate 13 I provide an opening 16 which has associated with it a door 18 pivoted to the plate 13 at the point designated by the reference character 19. The pivoted door 18 is adapted to close the opening 16, and as will subsequently appear herein said door may be operated at the will of the operator to withdraw same from said opening. 20 designates a coil spring which is associated with the door 18 in a manner to cause said door to be normally maintained in a closed position, and 21 designates a connector which is connected at one of its ends to the door 18 and at its opposite end to a foot pedal (not shown) whereby said door may be moved to an open position when desired. 17 designates a stop which limits the downward movement of the portion of the door 18 which closes the opening 16.

The rear wall 2 is provided with an extended bearing portion 2' in which a shaft 22 is supported in the usual manner by suitable roller bearings 23', the inner portion of said shaft 22 being extended inwardly into the

interior of the housing B as shown clearly in Fig. 2. Mounted on the inner end portion of the shaft 22 for rotary movement with said shaft is the rotor R of my improved sand screen which rotor includes a fly wheel 23. The fly wheel 23 has one or more arms 24 providing sand impellers associated with it, three of said arms being shown in the drawing, and I prefer that the arm or arms 24 shall extend from the hub portion of the fly wheel approximately to the peripheral face thereof as shown in Fig. 1. 25 designates a ring (Fig. 2), which is arranged at the forward edges of the arms 24. The ring 25 is arranged in a plane which is parallel with the plane in which the plate 13 is arranged and said ring may be formed integral with the arms 24, or if desired, may be in the form of a separate element which is secured by suitable fastening means to said arms. Formed on each of the arms 24 at the outer end thereof is a portion of increased thickness, said portions being designated by the reference character 24' in the drawing, and removably fixed to said thickened portion of each arm by suitable fastening devices is a wear plate 26. The wear plates 26 are arranged so that the outer edges thereof are in close proximity to the inner face of the cylindrical wall 8 and said outer edges of said wear plates sweep along the inner face of said cylindrical wall when the rotor R is subjected to rotary motion. The forward edges of the arms 24 are inclined inwardly and downwardly from the position of the ring 25 to provide a space between the inner face of the plate 13 and said inclined forward edges of the arms 24 which space is approximately cone-shaped (Fig. 2).

27 designates the sieve of my improved sand screen which is fixed to the shaft 22 so that said sieve will rotate with said shaft, the connection between the sieve and the shaft being effected by providing the shaft 22 with a reduced screw-threaded portion 22' which is extended through an aperture formed through the rear wall 27' of the sieve on which screw-threaded portion 22' a nut 28 is screwed. The rear wall 27' of the sieve 27 is confined between the nut 28 and a shoulder 29 formed on the shaft 22 whereby said sieve is rigidly fixed to said shaft. The sieve 27 is located in the more or less conical space between the inclined forward edges of the arms 24 and the inner face of the plate 13, said sieve itself preferably being conical shaped as shown clearly in Fig. 2, and said sieve being provided with an annular seat 30 shaped to receive a corner portion of the ring 25. In view of this arrangement it is obvious that the forward portion of the sieve 27 is supported by the ring 25 whereby said sieve becomes a fixed part of the rotor R. The sieve is, of course, provided with a plurality of apertures through which the sand being acted

upon by the sand screen passes, said apertures, which are designated by the reference character 31 in the drawing being preferably elongated and being of any suitable width.

In the operation of my improved apparatus sand to be aerated and otherwise prepared for use in molds is shoveled into the chute 15 and said sand will immediately pass through the opening 14 in the plate 13 into the interior of the cone-shaped sieve 27. The sieve 27, together with the other parts of the rotor R of the sand screen is rotating at this time and therefore the particles of sand of a size to permit it will pass through the apertures 31 of the sieve into the interior of the housing of the apparatus where said sand will fall to the lower portion of the cylindrical wall 8. The arms 24 of the rotor R rotate rapidly in the direction indicated by the arrow in Fig. 3 and as a result thereof the wear plates 26 on said arms will contact with the sand in the bottom portion of the housing and drive said sand forcibly through the discharge spout 9 whence it passes through the air and is deposited in a heap some distance from the apparatus. Large particles and foreign elements in the sand which are too large to pass through the apertures 31 in the sieve will roll down the inclined wall of said sieve and will gather adjacent to the door 18 from which position they may be removed by depressing the foot pedal (not shown) to which the connector 21 is attached whereby said door 18 will be moved to an open position, thus permitting the large particles and foreign elements referred to pass through the opening 16.

When the apparatus is in operation the very rapid rotation of the arms 24 will result in air being drawn through the apertures 31 of the sieve into the interior of the housing of the apparatus, the rapidly moving arms 24 creating suction which results in such movement of air. It follows therefore that this passage of air through the apertures of the sieve, together with the centrifugal force created by the rapidly rotating parts of the apparatus, will cause the sand to be fed rapidly and readily through said apertures whereby the sand is aerated and packing of sand at the apertures mentioned is prevented.

While I have illustrated and described the sieve of my apparatus as being approximately conical in shape I do not wish to be limited to the use of a sieve of such shape as my invention contemplates the use of a sieve of any shape which may be located within the housing of the apparatus.

I claim:

1. A sand screen comprising a housing having inlet and discharge openings, an impeller arranged for rotary movement within said housing by which sand is forcibly driven from said housing through the discharge opening thereof, a conical sieve located with-

in said housing through which the sand passes before being acted on by said impeller, said sieve being rotatable with said impeller, and a fly wheel located within said housing immediately adjacent to and rotatable with said impeller. 70

2. A sand screen comprising a housing having inlet and discharge openings, one or more arms providing impellers arranged for rotary movement within said housing by which sand is forcibly driven from the housing through the discharge opening thereof, a sieve located within said housing through which the sand passes before being acted on by said impellers, and a fly wheel located within said housing to which said impellers are rigidly fixed, said sieve being rotatable with said impellers and said fly wheel and said impellers being located in close proximity to said sieve. 75

3. A sand screen comprising a housing having inlet and discharge openings, an arm providing an impeller arranged for rotary movement within said housing by which sand is forcibly driven from the housing through the discharge opening thereof, a sieve located within said housing through which sand passes before being acted on by said impeller, said sieve being rotatable with said impeller, and a fly wheel to which said impeller is rigidly fixed. 80

4. A sand screen comprising a housing having inlet and discharge openings, one or more radial arms providing impellers arranged for rotary movement within said housing by which sand is forcibly driven from the housing through the discharge opening thereof, a sieve movable with said impellers within the housing through which sand passes before being acted on by said impellers, a fly wheel to which said impellers are rigidly fixed, and wear plates removably secured to said arms and serving as the portions thereof which contact with the sand to drive same from the housing. 100

In testimony whereof, I have hereunto set my hand.
